TRIGGER-PULL MEASURING DEVICE

Stephen T. Novak, Dayton, Ohio

Application November 14, 1942, Serial No. 465,568

6 Claims. (Cl. 73—167)

(Granted under the act of March 3, 1883, as amended April 30, 1928; 370 O. G. 757)

The invention described herein may be manufactured and used by or for the Government for governmental purposes, without the payment to me of any royalty thereon.

This invention relates to a device for measuring the force (in pounds) necessary to operate the trigger of firearms (trigger-pull). The object of invention is to provide a trigger-pull measuring device which will be relatively inexpensive to construct, which will be adaptable for production measuring and which may be operated by unskilled operators. For the attainment of these and such other objects as may herein appear or be pointed out I have shown an embodiment of my invention in the accompanying drawing.

The firearm to be tested, in the illustration, a rifle, is held firmly against recoil between two stops 1 and 2. At the finger side of the trigger is adjusted one end (the right, as seen in the figure) of a slide bar 4, which is guided by a stud 3 fixed to the machine frame and received in elongated slot 4s of bar 4. The said (right) end of bar 4 is provided with a pin 4p which abuts against the trigger. Pin 4p may be removably or adjustably mounted on bar 4, to facilitate its positioning against the trigger. The other (left) end of bar 4 is articulated to the distal end of a lever 5 pivotally mounted in a dependent position from the machine frame, at 5a.

A pneumatic arrangement is employed for turning lever arm 5 to the left (clockwise) to pull bar 4 and its pin 4p leftwardly to fire the rifle, comprising a bellows 10 effective, upon the introduction of air pressure in its chamber 11, to force bellows rod 12 to the left; rod 12 is articulated to the said lever arm 5. Air pressure is conducted from a source of air pressure 16, through a control valve 15, a second valve 14 and pipe T 13 (more particularly, the line direction thereof), to the bellows chamber 11. The branch outlet of T 13 is connected, through the line direction of a second T 17, to a control valve 18 which is connected to exhaust 19.

Valves 15 and 18 are operated together, as "gang valves" by means of a link 20. Gang valves 15, 18 are so arranged, and connected by link 20, that when one is opened, the other is closed and vice versa. After the firearm to be tested is placed against stops 1 and 2, as already explained, the link 20 is moved, by means of a handle 20h thereon, in position to open gang valve 15 and to close gang valve 18 (to exhaust 19). The air pressure, conducted to bellows chamber 11 (as traced above), forces lever 5 leftward, the latter pulling bar 4 in that direction. Leftward movement of

the parts continues until the gun fires. To measure the air pressure required to pull the gun trigger, a pressure gauge 7 is connected to the branch outlet of T 17.

To permit a reading of the maximum pressure reached by gauge 7 (which is the trigger-pull in pounds), the following arrangement is provided to maintain the said maximum reading (trigger-pull). The valve 14, which is in the supply line to the bellows chamber 11 (as already described), has a piston 21 connected by rod 22 to the lever arm 5. When the air pressure in bellows cylinder 11 has reached a pressure to turn lever arm 5 sufficiently to the left, the further leftward movement of the lever arm permitted by the sudden release of resistance presented by the trigger will pull rod 22 and its piston 21 to a position shutting off further air pressure to the chamber 11.

After the maximum reading of gauge 7 has been noted, the air pressure in the system is released by moving link 20 in a direction to shut inlet valve 15 and to open outlet valve 18 to exhaust; the gang valves are held in this position until the air pressure in the system has been released. The parts are returned rightwardly by a spring 5s one end of which is secured to lever 5 and the other anchored to the machine frame.

To check the calibration of the gauge a pulley-weight 30 is connected by a cord 31 to the end of bar 4, as shown in dot-and-dash lines in the figure. The reading taken when the air pressure just starts to pull the weights is checked against the calibrating weights.

I claim:

1. In a device for measuring the trigger-pull of firearms, the combination of means for holding the firearm, a lever pivotally mounted at one end and provided with a spring urging it in one direction, a bar articulated to the distal end of the said lever and mounted for an extent of sliding movement, a pin provided at the distal end of the said bar and adapted to be placed in abutting relation to the trigger of the firearm, a bellows having a rod articulated to the said lever and adapted to turn the lever in a direction opposite to the said spring-urged direction, a source of air pressure, an inlet valve leading to the said source, an exhaust outlet valve leading to the atmosphere, a common gang control for the said two valves, pipe means connecting each of the said two valves to the said bellows, a pressure gauge in the said pipe connection between the bellows and the exhaust outlet valve, and a shut-off valve in the said pipe connection between the bellows and the inlet valve provided with a piston

rod articulated to the said lever adapted, when the pressure in the bellows reaches a maximum sufficient to pull the trigger and discharge the firearm, to close the said shut-off valve whereby the said gauge will remain at the said maximum reading after the said discharge of the firearm.

2. In a device for measuring the trigger-pull of firearms, the combination of means for holding the firearm, a lever pivotally mounted at one end and provided with a spring urging it in one direction, a bar articulated to the distal end of the said lever and mounted for an extent of sliding movement, a pin provided at the distal end of the said bar and adapted to be placed in abutting relation to the trigger of the firearm, a bellows having a rod articulated to the said lever and adapted to turn the lever in a direction opposite to the said spring-urged direction, a source of air pressure, an inlet valve leading to the said source, an exhaust outlet valve leading to the atmosphere, a common gang control for the said two valves, pipe means connecting each of the said two valves to the said bellows, a pressure gauge in the said pipe connection between the bellows and the said exhaust outlet valve, and a shut-off valve in the said pipe connection between the bellows and the said inlet valve, the said shut-off valve being provided with a piston rod articulated to the said lever adapted, when the pressure in the bellows reaches a maximum sufficient to pull the trigger and discharge the firearm, to close the said shut-off valve whereby the said gauge will remain at the said maximum reading after the said discharge of the firearm.

3. In a device for measuring the trigger-pull of firearms, the combination of means for holding the firearm, a lever pivotally mounted at one end, a bar articulated to the distal end of the said lever and mounted for an extent of sliding movement, a pin provided at the distal end of the said bar and adapted to be placed in abutting relation to the trigger of the firearm, a bellows having a rod articulated to the said lever, a source of air pressure, an inlet valve leading to the said source, an exhaust outlet valve leading to the atmosphere, a common gang control for the said two valves, pipe means connecting each of the said two valves to the said bellows, a pressure gauge in the said pipe connection between the bellows and the said exhaust outlet valve, and a shut-off valve in the said pipe connection between the bellows and the said inlet valve, the said shut-off valve being provided with a piston rod articulated to the said lever adapted when

the pressure in the bellows reaches a maximum sufficient to pull the trigger and discharge the firearm, to close the said shut-off valve whereby the said gauge will remain at the said maximum reading after the said discharge of the firearm.

4. In a device for measuring the trigger pull of fire arms, the combination with means for holding the fire arm, a lever pivotally mounted at one end and a bar articulated to the free end of said lever and mounted for an extent of movement, a pin at the forward end of the bar and adapted to be placed in abutting engagement with the trigger of the fire arm, a pneumatic circuit for moving said lever including an air tight chamber having a bellows therein having operative connections with said lever to move the same, a shut-off valve and a pressure gage, said shut-off valve being located between the pressure gage and the air supply, the shut-off valve being connected with the lever and operated thereby to shut off and maintain the pressure in said pneumatic circuit between said valve and pressure gage upon the fire arm discharge to preserve the maximum gage reading.

5. In a device for measuring the trigger pull of fire arms, means for holding the fire arm, means including a lever for moving the trigger of said fire arm, a pneumatic circuit having operative connections with said lever to move the same, a pressure gage in said circuit, a shut-off valve operated by said lever upon the discharge of the fire arm, said shut-off valve being located between the pressure gage and the air supply whereby upon the operation of said valve the pressure in the pneumatic circuit will be maintained to preserve the maximum gage reading.

6. A device for measuring the trigger pull of a fire arm comprising means for holding the fire arm, a pivoted lever, a bar reciprocated by said lever and having means adapted for abutting engagement with the trigger of the fire arm, a pneumatic circuit having valve controlled inlet and a valve controlled outlet, operative connections between said circuit and said lever for moving the lever, a pressure gage in the circuit, a shut-off valve between the air supply and the pressure gage and operated by the lever upon the discharge of the fire arm, said shut-off valve operating upon the discharge of the fire arm to trap the air in said circuit between the shut-off valve and outlet to maintain the pressure in the circuit sufficiently long to permit the reading of the gage.
